UNITED STATES PATENT OFFICE.

FOORD VON BICHOWSKY AND JOHN HARTHAN, OF GLENDALE, CALIFORNIA.

PROCESS OF PRODUCING CYANIDES.

1,417,702.

Specification of Letters Patent. Patented May 30, 1922.

No Drawing.

Application filed October 25, 1920. Serial No. 419,458.

To all whom it may concern:

Be it known that we, FOORD VON BICHOWSKY and JOHN HARTHAN, citizens of the United States, and residents of Glendale, county of Los Angeles, State of California, have invented a new and useful Process of Producing Cyanides, of which the following is a specification.

The present invention relates in general to the production of cyanides and has reference more particularly to an improved process of production.

We have discovered that titanium nitrides, under which term we preferably include compounds containing only titanium and nitrogen as well as the so called titanium cyanonitrides, can be readily converted into cyanides of the alkali metals by heating the selected titanium compounds with a suitable inorganic alkali metal salt together with a reducing agent. We have further discovered, that the reaction may be carried out without the use of free carbon.

By a suitable alkali metal salt, we preferably include such compounds as formates, acetates, oxalates or oxides, hydroxides, carbonates or other salts of sodium, or potassium, or if desired mixtures of the above. For a reducing agent we preferably employ iron filings, which have become saturated with iron carbide. The formation of such filings we have described in two previous applications covering a process of producing titanium nitrogen compounds Nos. 385,561 and 385,562, filed June 1st, 1920, by heating titanium oxide and iron, together with sodium carbonate, with methane (natural gas) and nitrogen.

The mass so obtained after mechanically removing the free carbon is most suitable for our new process as the iron present, with the titanium nitrides, is saturated with dissolved carbon and iron carbide is therefore present in an impure form.

The process of the present invention is particularly valuable, since the titanium is easily recovered from the reaction mass and used over again. While the iron, present as such in the mass, is freed from carbon, and its melting point raised, which is of value when reusing the said iron in a newly pre-

pared and unnitrified catalytic mass. Also by avoiding the use of free carbon a more uniform reaction results and the final product is easier to recover in a pure uncolored condition. In addition the amount of alkaline metal compound can be reduced to more nearly the theoretical amount.

For the purpose of this invention, the titanium nitrides and titanium cyano-nitrides are equivalents.

The following will serve to illustrate further the nature of our invention, which, however, is not confined necessarily to these examples, and the method of carrying it into practical effect.

As an example:

Melt together for about thirty minutes at a bright red heat two parts of the finely ground titanium nitride containing mass and about three parts of anhydrous sodium carbonate. The carbon monoxide evolved during heating may be collected and burned. When the melt is cold, the sodium cyanide contained therein can be recovered in any convenient manner. The reaction which takes place can be represented by the equation:

As another example:

Melt together for thirty minutes at a temperature of about 950° C., a mixture of equal parts of the finely ground titanium nitride containing mass and dry sodium formate. The reaction which takes place can be represented by the equation:

The cyanide can be either recovered as such or converted into ammonia by treating the reaction mass with steam according to the well known procedure.

We claim:

1. The production of cyanides of the alkali metals which consists in heating titanium nitrides with a carbide of iron in the absence of free carbon and in the presence of an alkali metal salt.
2. The production of sodium cyanide

which consists in heating a titanium nitride with a carbide of iron in the presence of a sodium salt.

3. The production of sodium cyanide which consists in heating a titanium nitride with a carbide of iron in the presence of a sodium formate.

4. The herein-described process of producing cyanide which consists, heating a titanium compound with an alkali metal salt together with a reducing agent in the absence of free carbon. 10

FOORD VON BICHOWSKY.
JOHN HARTHAN.
